G. H. MARSH.

METHOD OF SIMULTANEOUSLY EMBOSsing AND PRINTING.

APPLICATION FILED Oct. 19, 1908.

936,335.

Patented Oct. 12, 1909.

UNITED STATES PATENT OFFICE.

GEORGE H. MARSH, OF RAHWAY, NEW JERSEY.

METHOD OF SIMULTANEOUSLY EMBOSSED AND PRINTING.

936,335.

Specification of Letters Patent. Patented Oct. 12, 1909.

Application filed October 12, 1908. Serial No. 458,448.

To all whom it may concern:

Be it known that I, GEORGE H. MARSH, a citizen of the United States, and resident of Rahway, in the county of Union and State of New Jersey, have invented certain new and useful Improvements in Methods of Simultaneously Embossing and Printing, of which the following is a specification.

The object of my invention is to emboss cards, letter paper, envelopes and other printing matter, and simultaneously print upon the embossed or raised surface of the card or paper and to accomplish such embossed printing with ordinary type set in a type chase or form in usual manner.

The manner of carrying out my invention will be more fully hereinafter described and then particularly pointed out in the claims.

Reference is to be had to the accompanying drawings which illustrate the various steps taken in carrying out my invention, wherein,

Figure 1 is a face view of the type form set to emboss and print a card; Fig. 2 is a face view of a card adapted to one of the first steps; Fig. 3 is a section thereof on the line 3, 3, in Fig. 2; Fig. 4 is a face view illustrating a part that aids in the embossing; Fig. 5 is a section thereof on the line 5, 5, in Fig. 4; Fig. 6 is a view similar to Fig. 4 illustrating a further step to be taken; Fig. 7 is a cross section on the line 7, 7, in Fig. 6; Fig. 8 is a face view illustrating the protecting sheet used during printing; Fig. 9 is a cross section on the line 9, 9, in Fig. 8; Fig. 10 is a detail section through the type form, illustrating the position of the type ready to print upon the embossed surface; Fig. 11 is a diagrammatic view of a portion of a printing press equipped for the simultaneous embossing and printing; Fig. 12 is a face view of an embossed and printed card, and Fig. 13 is a section thereof on the line 13, 13, in Fig. 12.

Similar numerals of reference indicate corresponding parts in the several views.

Assuming that a visiting or business card is to be simultaneously embossed and printed on at least one portion thereof, the type therefor is set in the ordinary manner, as illustrated in Fig. 1, except that surrounding the part to be embossed and printed, such for instance as the name, indicated at 1 in Fig. 1, the type thereof is surrounded by suitable brasses 2, which are locked in the form type high. The form is then placed in

the press. An impression is then taken upon a suitably thick card A; and an impression taken upon the platen sheet B, and upon a sheet C, the type high brasses 2 printing the border line 3 which indicates on the card and sheets the position of the type within the brasses. The part of the card A within the printed line or border 3 is then cut out, leaving an opening, as indicated at 4, and such cut out piece a (or a similar piece a little thicker, say one ply thicker than piece a) is pasted upon the platen sheet B within the printed line or border 3, directly over the name that was printed within the same, in position indicated in Figs. 4 and 5, so that the piece a will aline in the press with the space within the brasses 2. The type form having been removed from the press is then placed upon card A so that the type within the brasses 2 will aline with the opening 4 in said card (see Fig. 10.) The type are then loosened and the type within the brasses 2 are pushed through the opening 4 of card A against the rest or table so that the printing surface of said type will be below type high, the brasses and the balance of the type of the form all remaining type high. The type are again locked in the chase and the latter with the card A in position as above described are secured in the press, whereby in printing position the type within the brasses will remain below type high, in line with the strip a upon platen sheet B. If preferred, a relatively thin piece of paper or cloth d may be pasted upon platen sheet B over the strip a, as in Figs. 6 and 7. The sheet C is also cut out at e within the border or line 3 to correspond with the type within the brasses, a margin e of suitable width or as much as possible is left between the edges of opening a and the border 3 (Fig. 8), and sheet C is also cut out in line with any other type of the type form to be printed, as indicated at 5 in Fig. 1, such cut out part being indicated at e in Figs. 8 and 9, to permit all the type to print through sheet C. Said sheet is then secured to the gripper-fingers G, of the press H, in such position that the openings of sheet C will, in the position when the impression is taken, aline with the type within the brasses 2 and with the strip a upon the platen sheet B, and with any other type. As a protection against wear, and to prevent the brasses making impression on the stock to be embossed and printed I paste upon sheet C, a piece of suit-

able cloth, such as gummed cloth, cut through in line with and corresponding to the openings in sheet C and I may also attach sheet C to the gripper fingers by similar pieces of gummed cloth.

The parts being fitted in the press, the card I to be printed is placed upon the platen H^2 in usual manner lying over the strip a , and when the card is moved by the platen toward the type the strip a will push the card through opening c of sheet C and into the space within the brasses into contact with the type within the brasses and the co-action of the brasses with the strip a causes the card in line with such strip to be bent and embossed by a single stroke simultaneously with the printing upon such embossed part of the card as indicated generally at J in Figs. 12 and 13. The sheet C at such time takes the impression from the brasses and thus protects the printed matter from the ink applied upon such type high brasses by the inking roller. The margin of sheet C at opening c aids in doing the embossing on the stock to be printed. During such printing any other type of the form will simultaneously print through the corresponding openings c of sheet C.

While I have illustrated the simultaneous embossing and printing in one place only on a card, it will be understood that any desired number of embossed and simultaneously printed portions of the card or other paper may be accomplished by arranging brasses around the type of such portions intended to be embossed and printed, and placing corresponding pieces a upon the platen, the type within such brasses being pushed back below type high in the manner before described, and such type as are not to serve for embossing will be left type high.

By means of my invention it is not necessary to produce embossing plates for any matter to be embossed and printed upon the embossed places, for by providing suitable brasses any desired matter can be set by type in the usual manner, with the brasses surrounding the type to print upon the embossed surface or surfaces, whereby such brasses may be used in various shapes.

Although I have described my invention in connection with the printing of a card it will be understood that the same may be used for printing letter heads, bill heads, envelopes, and any other desired printed matter, where one or more portions thereof are to be raised or embossed with printing upon such embossed surfaces.

While I have referred to the parts 2 as brasses it will be understood that I mean

any similar piece of metal of suitable width and length and type high when standing on edge, adapted to be locked in the form surrounding the type to print upon the raised surface of a sheet.

65

Having now described my invention what I claim is:—

1. The method of simultaneously embossing and printing consisting in setting type below type high within type high impressing brasses, applying a strip upon a platen sheet in operating alinement with the space within the brasses, applying ink upon such type while below type high, impressing a card or sheet by said strip into the space between the brasses and in contact with the type within the brasses to print upon the thus raised portion of the sheet, and protecting the sheet from being printed by the brasses.

75

2. The method of simultaneously embossing and printing consisting in setting type and brasses surrounding the type type high, depressing the type within the brasses below type high, and maintaining all the type and brasses in such relation, attaching a strip upon the platen in operative alinement with the space within the brasses, taking an impression upon matter to be printed and simultaneously raising such matter by causing the strip to push the matter between the brasses against the type within the brasses.

80

3. The method of simultaneously embossing and printing consisting in setting type and brasses type high with type within the brasses, taking an impression of the type and brasses upon a card, cutting out the card within the impression of the brasses, placing the type upon such card with the opening in the card alined with the type within the brasses, pushing said type below type high through the opening in the card, locking the type and placing them and said card in a press, applying a strip to the platen corresponding to the strip cut out of such card and in operative alinement with the space within the brasses, applying a prepared sheet to grippers having openings cut out in line with the type within the brasses, placing a card or sheet against the strip on the platen, and then pushing the card or sheet through the opening in the gripper sheet and into the space within the brasses into contact with the sunken type within the brasses.
